UNITED STATES PATENT OFFICE.

FRANK F. DENDINGER, OF NORFOLK, NEBRASKA.

TRAFFIC SIGNAL.

Application filed June 11, 1924. Serial No. 719,394.

This invention relates to traffic signals and it consists in the novel features herein-after described and claimed.

An object of the invention is to provide 5 a signal adapted to be used at the intersection of streets to direct the movement of the traffic and pedestrians and thereby eliminating the necessity of traffic officers at such places.

10 A further object of the invention is to provide a signal adapted to be electrically operated at intervals to lower arms part way across the street at diagonal corners and at the same time raising the arms at 15 the opposite corners and at the same time move short arm sections across the sidewalk thereby warning the pedestrians that the cross street is open to vehicular traffic.

The arms which are lowered across the 20 street are positioned at points high enough above the level of the street to permit automobiles to clear or pass under them when they are lowered, but these arms may be provided with chain sections which hang 25 pendent and in the event that the driver of a machine should disregard the signal and attempt to pass under the arm when it is lowered, the said chain sections will strike the wind shield of the machine of which 30 the driver is disregarding the signal. The arm may be provided with a colored electric lamp bulb which will illuminate when the said arm is lowered and an electrically operated bell or other audible signal may 35 be connected in the circuit which illuminates the lamp bulb.

In the accompanying drawings:

Figure 1 is a diagrammatic view indicating the intersection of several streets and 40 with the traffic signal arranged in system thereon.

Figure 2 is a side elevation of the traffic signal with parts thereof shown in section.

Figure 3 is a horizontal sectional view of 45 the same.

Figure 4 is a fragmentary side elevation of the modified form of the traffic signal.

The signal comprises a post 1 which is 50 hollow and which is adapted to be erected adjacent the corner of intersecting streets and preferably at the curbing of the sidewalk. The upper portion of the post 1 is slotted as at 2. A shaft 3 is journaled transversely of the post 1 at the lower end 55 portion of the slot 2 and a relatively long arm 4 is mounted upon the shaft 3. The

arm 4 is adapted to swing transversely across the street when it is lowered. A transparency 5 is carried at the free end portion of the arm 4 and is preferably provided with 60 a legend adapted to indicate that the street is closed, as for instance, the word "Stop".

The arm 4 is provided at its inner end with a gear segment 6 arranged concentrically with relation to the shaft 3. A rack 65 bar 7 is mounted for longitudinal movement through a guide 8 in the post 1 and the teeth of the rack bar 7 mesh with the teeth 6. The lower end of the bar 7 is pivotally connected with the upper end of 70 the core 9 arranged for sliding movement in a magnet 10 which is housed within the lower portion of the post 1. Electric wires 11 are adapted to conduct the electric current 75 to the magnet 10. A relatively short arm 12 is connected with the shaft 3 and is provided with a danger sign 13. The arm 12 is adapted to swing across the sidewalk when the arm 4 is swung across the street or roadway. An electric bulb 14 is 80 carried by the arm 4 and electric wires 16 extend along the said arm and are adapted to conduct the electric current to the bulb 14. One of the wires 15 leads to a source of electric supply and the other wire 85 15 connects with a terminal 16 adapted to have contact with a terminal 17 mounted upon the post 1 when the arm 4 is swung to a lowered position as shown in Figure 2. Therefore when the arm 4 is swung to 90 a lowered position, the bulb 14 is illuminated and in the event that an electric bell or other audible signal is connected with the wires 15, the said audible signal is sounded.

95 As illustrated in Figure 4 of the drawings, chain sections 18 may be connected with the arm 4 and in the event that the driver of a machine should attempt to pass under the arm while it is in the lowered position, the said chain sections will strike the windshield of his machine and break the same and thereby effectually warning the driver that the street is closed to vehicular traffic.

100 The post 1 arranged at diagonal opposite corners of the intersecting streets is connected with the same electric wires 11 and each set of electric wires 11 is provided with a switch 20 which may be closed and the 105 said wires connect with the batteries or generator 21. Therefore when the switch 20

- is closed, the arms upon the post at the diagonal opposite corners are simultaneously swung across the street and the sidewalks thus serving as warnings or signals that
- 5 the movement of traffic along the said street is temporarily suspended or interrupted and at such time the switch which controls the supply of current to the signals at the intersecting streets may be opened, thus permitting
- 10 the magnets 10 to draw the cores 9 whereby the rack bars 7 are moved longitudinally and the arms 4 are swung to vertical positions, and this indicates that the said street is open to the movement of vehicular traffic and pedestrians.
- 15

Having described the invention, what is claimed is:

A traffic signal comprising a hollow cylindrical post having a slot, an electro-magnet mounted in the bottom of the hollow

post, a bearing positioned in the post above the electro-magnet and attached to the inside surface of the post so that its bore is offset in relation to the axis of the post, a bar slideable in the bearing to move in parallel spaced relation with the axis of the post, said bar being connected with the core of the magnet, and provided with rack teeth adjacent its upper end, a shaft extending transversely through the upper interior of the post, an arm extending through said slot and pivoted at one end to said shaft, said pivoted end being provided with teeth meshing with the teeth of the bar whereby the arm may be swung upon energization of the magnet.

In testimony whereof I affix my signature.

FRANK F. DENDINGER.
